UNITED STATES PATENT OFFICE

154,856

DESIGN FOR A CARVING SET HOLDER

James L. Hvale, Chicago, Ill., assignor to Ekco Products Company, Chicago, Ill., a corporation of Illinois

Application February 19, 1948, Serial No. 144,595

Term of patent 14 years

(Cl. D44—29)

To all whom it may concern:

Be it known that I, James L. Hvale, a citizen of the United States, residing at Chicago, in the county of Cook, State of Illinois, have invented a new, original, and ornamental Design for a Carving Set Holder, of which the following is a specification, reference being had to the accompanying drawing, forming part thereof.

Fig. 1 is a top perspective view of a carving set holder, showing my new design.

Fig. 2 is a top plan view thereof.

Fig. 3 is a side elevational view thereof.

Fig. 4 is a cross sectional view taken on line 4—4 of Fig. 2.

The dominant feature of the design resides in the portion shown in full lines.

I claim:

The ornamental design for a carving set holder, as shown and described,

JAMES L. HVALE.
